UNITED STATES PATENT OFFICE.

ANDREW FREDERICKSON, OF CHICAGO, ILLINOIS.

COMBINED TOBACCO POUCH AND PIPE-FILLING DEVICE.

Application filed May 1, 1926. Serial No. 106,120.

This invention relates to tobacco pouches and its main object is the provision of a device for filling pipes with tobacco in combination with the pouch.

5 Another object of the invention is the provision of the device for filling pipes with tobacco whereby predetermined amount of tobacco may be had before filling the pipe therewith.

10 With the above general objects in view and others that will appear as the nature of the invention is better understood, the same consists in the novel construction, combination and arrangement of parts hereinafter 15 more fully described, illustrated in the accompanying drawing, and pointed out in the appended claim.

In the drawing forming a part of this application and in which like designating 20 characters refer to corresponding parts throughout the several views,

Fig. 1 is a view, partly in elevation and partly in cross-section, showing the position of the device when the pipe is about to be 25 filled with tobacco;

Fig. 2 is a cross-sectional view taken on line 2—2 of Fig. 1; and

Fig. 3 is a cross-sectional view taken on line 3—3 of Fig. 1.

30 The invention embodies a pouch 10 provided with flap 11 overlying the mouth of the pouch through which the tobacco is supplied thereto. The flap is provided with conventional clasp buttons 12 for securing 35 the flap to the pouch. At the opposite end the pouch is provided with metallic cylinder 13 having at each of its ends an annular rim 14 which has a central annular groove 15 for receiving the adjacent portion of pouch, 40 which arrangement prevents the longitudinal shifting of the cylinder 13 in respect of pouch 10. Near one of its ends cylinder 13 is provided at its upper portion with an opening 16 through which tobacco is permitted 45 to enter cylinder 13 from pouch 10. Said cylinder 13 is further provided with an annular plate 17 which is fitted over the upper portion of cylinder 13 and is adapted for sliding movement thereupon longitudinally 50 of the cylinder. The purpose of this plate 17 is to regulate the amount of tobacco which is permitted to enter the cylinder 13 from pouch 10 through opening 16, according to the size of the pipe and the amount of tobacco required to fill the same.

Substantially in its central portion and

longitudinally thereof the cylinder 13 is provided with an oblong slot 18 for permitting the sliding movement of bolt 19. The head 20 of bolt 19 engages the adjacent edges of cylinder 13 and prevents the upward movement of bolt 19. Said bolt 19 further passes through an aperture made in the plate 17. The upper end of said bolt 19 is threaded for receiving nut 21 by means of which plate 17 is held in position in respect of cylinder 13.

From the hereinabove description it will be apparent that on loosening nut 21 plate 17 may be longitudinally shifted upon cylinder 13, slot 18 providing the guiding channel for bolt 19. It is further apparent that on shifting plate 17 toward the opening 16 said opening is made smaller by virtue of plate 17 which overlies part of said opening 75 and prevents tobacco from falling to cylinder 13 through the portion which is covered by plate 17.

The device further embodies plunger cylinder 22 which is adapted for sliding movement within cylinder 13. Said plunger cylinder 22 is provided at one of its ends with annular flange 23. The end of cylinder 13 adjacent opening 16 is provided with a concentric flange 24 which cooperates with flange 23 of plunger cylinder 22 for preventing the withdrawal of said plunger cylinder 22 from cylinder 13, as is apparent from Fig. 1. Plunger cylinder 22 at its outer end is provided with closure 25 through which matches 26 are supplied or withdrawn from said plunger cylinder 22.

When the device is in an inoperative position plunger cylinder 22 normally rests within cylinder 13 and entirely fills the said cylinder and by its periphery blocks opening 16 preventing the tobacco from entering cylinder 13. On withdrawing plunger cylinder 22 from cylinder 13, the position illustrated on Fig. 1, tobacco is permitted to enter cylinder 13 through opening 16. When a portion of tobacco has entered said cylinder 13 by pushing plunger cylinder 22 within cylinder 13 the tobacco within said cylinder 13 is forced to enter the bowl of pipe 27 the 100 pipe having been first positioned by its mouth at the end of cylinder 13 preparatory to charging operation by plunger cylinder 22 hereinbefore described, as illustrated on Fig. 1.

The end of pouch 10 adjacent cylinder 13 is of a round formation snugly fitting the

periphery of said cylinder as clearly seen on Figs. 2 and 3. In order to prevent any rotary shifting movement of cylinder 13 in respect of the enveloping end of pouch 10 a tubular clamp 28 is fitted over the pouch fabric and around the cylinder 13.

While there is described herein a preferred embodiment of the present invention it is nevertheless to be understood that minor changes may be made therein without departing from the spirit and scope of the invention as claimed.

What I claim as new is:

The combination with a tobacco pouch, of a cylinder removably carried in the pouch and having substantially the same length as the width of the pouch thereby to prevent distortion of the pouch, said cylinder having an opening near one of its ends permit-

ting entrance of tobacco thereto from the pouch, and another opening permitting removal of tobacco from the cylinder, a closure member for the entrance opening accessible only from within the pouch, means for ejecting tobacco from the cylinder, and a removable, spring metal clamping member of substantially the same length as the cylinder and being U-shaped in cross-section and having the same cross-sectional dimensions throughout its length, and fitting over that portion of the pouch engaging the cylinder and extending substantially from end to end of the cylinder for maintaining said cylinder in stationary position with respect to the pouch without distorting the pouch.

In testimony whereof I affix my signature.

ANDREW FREDERICKSON.
